UNITED STATES PATENT OFFICE.

GEORGE P. BUMP, OF LA CROSSE, WISCONSIN, ASSIGNOR TO BUMP'S PERFECTED
PAPER FASTENER CO., A CORPORATION OF WISCONSIN.

MACHINE FOR FASTENING PAPER OR LIKE SHEETS TOGETHER.

1,104,622.

Specification of Letters Patent. Patented July 21, 1914.

Application filed May 5, 1913, Serial No. 765,626. Renewed June 10, 1914. Serial No. 844,364.

To all whom it may concern:

Be it known that I, GEORGE P. BUMP, citizen of the United States, residing at La Crosse, Wisconsin, have invented certain new and useful Improvements in Machines for Fastening Paper or like Sheets Together, of which the following is a specification.

The invention relates to a machine for making the form of paper fastener or tie disclosed in Letters Patent of the United States No. 1,009,644, dated November 21, 1911.

My present invention is an improvement upon that form of machine disclosed in Letters Patent of the United States No. 1,065,903, dated June 24, 1913, an example of such type of machine being illustrated in Letters Patent of the United States, No. 966,598, dated August 9, 1910, granted to R. B. Reasoner, my object being to increase the efficiency of the tool, reduce it to a minimum size for convenient handling, and to simplify and reduce the cost of manufacture.

The tool comprises generally two jaws, one carrying a die or shear plate and the other carrying a punch or cutter to cut a tongue from the sheets of paper which are to be fastened together, said cutter operating in conjunction with the shear plate to form this tongue. Associated with the tongue cutter is a folder and a needle, which move in unison therewith, the needle cutting a slit in the paper and having an eye into which the folder forces the end of the tongue, so that as the needle retracts through the slit in the superimposed sheets, it will draw the tongue therethrough and thus complete the fastening together of the sheets.

In the drawings Figure 1 is a side view of the complete tool; Fig. 2 is a part sectional view and elevation, the part shown in section being the lower handle with its housing; Fig. 3 is a sectional view of the upper handle with all the working parts connected therewith, the lower handle with its housing being removed; Fig. 4 is a side view of the lower handle and housing; Fig. 4^a is a bottom plan view of the lower handle member and housing; Fig. 4^b is an end elevation of the lower handle member and housing looking from the right of Fig. 4; Fig. 5 is a side view of the lower jaw detached; Fig. 6 is a detached plan view of the lower jaw;

Fig. 7 is a plan view of the stripper plate; Fig. 8 is a plan view of the shear plate; Fig. 9 is a side elevation of the upper jaw; Fig. 10 is an end view of said upper jaw; Figs. 11 and 11^a are respectively a side elevation and a plan view of the cutter or punch; Fig. 12 is a side view of the tongue tucker or folder; Fig. 12^a is a sectional view of Fig. 12 on line 12^a-12^a looking from the right; Figs. 13 and 13^a are respectively a side view and a plan view of the needle; Fig. 14 is a bottom plan view of Fig. 3. Figs. 15, 16 and 17 are views of details.

In these drawings, 1 is a shear plate and 2 the stripper plate which receive between them the sheets of paper which are to be fastened together, 3 is the tongue cutter or punch, 4 the needle, and 5 the tongue tucker or folder. The shear plate or die is carried by a lower jaw 6. This jaw may be constructed and arranged in various ways, but in the particular form shown it is secured to a lower handle member 7 by screws 8, 9, a pair of said screws being on each side of the tool, as will be hereinafter described. 70 The stripper plate 2 is secured at its rear end by a screw 10 to the shear plate, and this stripper plate is formed of spring metal the tendency of which is to close down upon the shear plate, it being normally held up by means hereinafter described. 80

The punch or tongue cutter 3, needle 4, and tucker or folder 5 are mounted upon an upper jaw 11, as will be hereinafter described. This upper jaw has a pin and slot connection at 12 with an upper handle lever 13, which latter is pivotally connected with the lower jaw 6 by the screws 8. The upper and lower jaws are further connected together by a pair of links 14 pivoted to the upper jaw at 15, and having a pin and slot connection at 16 with the lower jaw. The links are pivoted at 17 to the upper handle lever. 90

A spring 18 attached at one end to the upper jaw at 19 and at its other end to the pin 12 of the upper handle lever holds the parts normally in the position shown in Fig. 2, with the jaws separated and the stripper plate raised ready to receive the paper sheets 100 which are to be united. The immediate means for lifting the stripper plate may assume various forms, but in the particular construction shown as exemplifying my invention I employ arms 20 extending up 105

110

from the stripper plate and having their upper curved ends resting on the ends of the links 14. These arms extend up across the space between the jaws and are operated 5 from the movement of the upper jaw. As the upper handle lever is moved down to cause the punch to cut out the tongue from the paper, the needle to form the slit, and the tucker to turn the tongue to enter the 10 eye of the needle or slitter, the spring stripper plate will move toward the shear plate at the same speed that the punch, tucker and needle advance to operate upon the paper sheets, or in other words at the same 15 speed of closing movement of the jaws, and because the stripper plate is arranged in a slightly lower plane than the lower ends of said parts just mentioned, said stripper plate will engage and securely hold the paper 20 sheets before the punch tucker and needle operate thereon, the stripper plate now remaining at rest while the further closing of the jaws proceeds and the punch, tucker and needle are operating to make the tie. By 25 thus firmly clamping the paper sheets in advance of the action of the tie forming elements thereon, a smooth clean tongue will be cut which will work equally well in fine as well as the heavier grades of paper, as 30 all buckling of the paper sheets is prevented.

The lower handle member is provided with a housing 21 and in the particular form shown this is an integral extension of the handle member. This housing receives the 35 upper handle, and all the working parts shown in Fig. 3, including the upper handle, and all these working parts can be removed from the housing as one body, this group of mechanism being shown in Fig. 3. This removal can be effected simply by removing the screws 8 and 9.

The lower handle member has no movement relative to the lower jaw they being fixed together or in effect integral with each 45 other, the upper handle being the only one to have pivotal movement in relation to the jaws. The lower handle, together with the lower jaw and the housing, may be said to be the stationary portion of the tool, and 50 that the upper handle, by moving down in relation to this fixed portion, causes the upper jaw to close upon the lower jaw, and it will be observed that the movement of the upper jaw at all times is such that it maintains its parallelism with the lower jaw and registers accurately therewith, insuring the proper registry of the punch or cutter, the needle and the tucker or folder with the 55 openings in the stripper plate and the co-operating parts of the shear plate. The construction just described permits ready access to the various parts. When the upper handle with its attached mechanism is assembled with the lower handle and its housing, this mechanism is protected and con-

cealed from view, as shown in Fig. 1. The lower portion of the upper handle fits within this housing also.

I prefer to form the upper handle member and the lower handle with its housing by stamping each of these parts from a single piece of sheet metal. The housing will be provided with a cover portion 22 which is secured by screws 23 to ears 24 bent in from the upper edges of the housing. This stamping for the lower handle and housing, as shown in Fig. 4, is provided with ears 25 having elongated openings 26 through which the screws 9 pass for holding the lower jaw 6 to the handle 7 and permitting 70 its adjustment, for which purpose also the lower jaw has elongated openings, as at 27, receiving the screws 8 which form the pivot connection of the upper handle member and serve also to connect the lower handle member, lower jaw, and upper handle together. The openings for these screws are located in the lower handle member, as at 28.

The lower jaw is preferably a sheet metal stamping having a bottom wall with up-standing side and end walls. It is provided with an opening 29 in its bottom wall. This lower jaw is of less width at its rear portion, as shown in Fig. 6 at 30, to accommodate the links 14 which lie outside of the 95 jaws and within the depending sides of the upper handle. To the wider part of the lower jaw the depending sides of the upper handle are pivoted. The shear plate 1 is held to the lower jaw by screws 31. The shear plate rests upon the upper edges of the end and side walls of the lower jaw, and it is narrowed at its rear portion to accommodate the lower ends of the upper handle member and the links 14. The spring stripper plate is secured at its rear end by the screw 10 and nut 32, the screw passing through the shear plate and the nut fitting between the side walls of the lower jaw to prevent turning. This stripper plate has 110 an opening 33 through which the punch 3 and tucker 5 pass, and an opening 34 through which the needle or slitter 4 passes. It also has an upstanding stud or lip 35 at the rear edge of the opening 33 for retracting the tucker or folder when raised, as in Fig. 3, and for retaining it in this position. While the control of this spring stripper plate may be effected in various ways, I prefer as in the particular form shown to form it with two integral arms 20 cut from the rear portion of the plate, and bent up therefrom with their upper ends suitably formed to engage and be lifted by a member or members moving with the upper jaw, which, in the present instance, I have shown as the upper ends of the links 14. The stripper plate, when lifted, is arrested by coming against the lower edges of the housing, the arresting bearing being preferably 115

120

125

130

throughout the length of these edges and the edge of the end wall of the housing. It will be observed in Figs. 1 and 3 that the stripper plate is parallel with the shear plate. This relation is substantially maintained in both the open and closed positions of the plates. In the open position it facilitates ready insertion of the paper sheets, and in the closed position it insures the firm holding or clamping of the paper throughout the inserted portion of the paper sheets while the tie is being formed. By utilizing the housing as the stop for arresting the lifting of the stripper plate, the space between the stripper plate and the shear plate may be left free and unobstructed for the insertion of the paper sheets for a considerable distance.

It will be observed that the lifting force exerted through the arms 20 is applied about midway of the length of the stripper plate, and this aids in the maintenance of the parallelism just mentioned, and another result of the arrangement is that the lifting arms are concealed and protected by the housing. These lifting arms embrace the upper jaw 11. This upper jaw is a sheet metal stamping having a top wall and side walls. It is located at its rear portion within the depending sides of the upper handle and at its front portion within the housing 21, lying close to the upper wall of said housing when in its normal open position, as shown in Fig. 2. It is concealed and protected by the housing and upper handle.

The punch or tongue cutter 3 is stamped up out of sheet metal with sides inclined in respect to each other to cut a V-shaped tongue. Within this punch the working end 49 of the tucker 5 is located, said tucker, in the particular form of my invention shown herein, being of spring metal, its upper end being turned downwardly, forwardly, and upwardly, providing a straight base portion 45 having integral side lugs 36 fitting between the adjacent edges of the tongue cutter and the shank of the needle 4. These side lugs are confined between projections 37, 38', forming integral parts of the tongue cutter 3 and needle shank, respectively. The upper end of the attaching or base portion of the tucker is provided with a notch at 38 which receives the upper bend of the metal strip from which the tucker is formed. The tucker moves down with the upper jaw, and hence its lower end rides off of the projection or stud 35 and moves to the right to fold the paper tongue cut by the punch 3 into the eye of the needle, this movement being due to the spring of the metal of which the tucker is composed. When the jaws separate, the tucker rides on the projection 35, and its work end moves leftward to the position shown in Fig. 3. These movements under constant use will produce

crystallization of the metal and consequent breakage were certain constructions of spring tuckers employed, but with the form shown a long spring strip is provided, the bend at the top being gradual and this merging ~~70~~ into a free downwardly extending portion, which connects by a gradual curve with the upwardly extending base or attaching portion. The spring action is thus distributed over a spring member of considerable length ~~75~~ instead of being confined to some one point or bend, and as a result of this new construction the life of the tucker is greatly increased. The needle or paper slitter 4 is also formed by stamping it up. It is provided with integral flanges 39 forming, with the main part of the needle, a shank, the edges of which, as above described, are aline with the edges of the attaching portion of the tongue cutter, and being provided with ~~80~~ the lugs 38', hold the tucker or folder in conjunction with said tongue cutter.

The tongue cutter or punch 3 and the needle or slitter 4 are held within the upper jaw by a pair of pins 40 passing through ~~85~~ notches 41 in the front edge of the punch, and bearing in the side walls of the jaw, and by a pair of pins 42 bearing in the side walls of the upper jaw and a wedge 43 interposed between the pins and the back face of the ~~90~~ shank of the needle.

The links 14 are stamped out of sheet metal with hollow journals 44 upset from the metal of the links, these journals extending outwardly and bearing in openings in ~~95~~ the sides of the upper handle member. This construction avoids the use of pivot pins, liable to drop out.

The upper handle is formed by stamping dies, and is all in one piece. It is slidably ~~100~~ connected to the upper jaw and pivotally connected by its extensions to the other jaw. It forms the fulcrum for the link connection, and in effect forms one member of said connection between the jaws, providing with ~~105~~ the links 14 a crossed link connection.

Both of the handles are provided with guard projections 40', these being curved to afford comfortable bearings for the hand. They prevent the hand from slipping too ~~110~~ far forward.

While I have referred to the member 4 as a needle, it will be understood that this may be otherwise constructed than with an eye, so long as it performs the functions of making the slit and drawing the end of the paper tongue up therethrough.

Where I have spoken of a shear plate or die on the lower jaw it will be understood that I do not limit myself to such plate or die formed separately from said jaw.

I claim:—

1. In combination in a machine of the class described, a pair of jaws, a needle with tongue cutting and folding means on one ~~120~~

jaw, a shear edge on the other jaw, handles connected with the jaws one of said handles and jaws being connected rigidly and a link connection between the jaws, substantially as described.

5. In combination in a machine of the class described, a pair of jaws, a needle with tongue cutting and folding means on one jaw, and a die on the second jaw, a handle carrying said second jaw rigidly, a handle having sliding connection with the first jaw and pivotal connection at its front end with the second jaw, and a link connection between the jaws having a sliding connection with the second jaw and pivoted to the first jaw, said link connection being journaled on the handle last mentioned, substantially as described.

6. In combination in a machine of the class described, a pair of jaws, a needle with tongue cutting and folding means on one jaw, a shear edge on the second jaw, a handle and housing connected to and in fixed relation to said second jaw, a handle slidably connected to the one jaw and pivotally connected to the second jaw, and a link connection between the jaws journaled on the pivoted handle member, said housing inclosing the working parts, substantially as described.

7. In combination in a machine of the class described, a pair of jaws the upper one carrying a needle with tongue cutting and folding means and the lower one carrying a shear edge, a handle and housing connected to and in fixed relation to the lower jaw, a handle having pivotal connection with the lower jaw, and sliding connection with the upper jaw, a link connection journaled on the pivoted handle and connecting the jaws, said housing and pivoted handle inclosing the upper jaw and the housing also inclosing a portion of said pivoted handle, the parts carried by the upper jaw and the link connection, substantially as described.

8. In combination in a machine of the class described, a pair of jaws movable toward and from each other while maintaining their parallelism, handles connected therewith, a needle with tongue cutting and folding means on one jaw, a shear edge on the other jaw and a housing inclosing the working parts and connected in fixed relation to one of the jaws and its handle and a link pivoted to the jaws and to the other handle, substantially as described.

9. In combination in a machine of the class described, an upper jaw, a needle with tongue cutting and folding means connected with the upper jaw, a handle connected with the upper jaw, a housing and lower handle formed in one piece, said housing having side walls and an end wall, and open at the rear and lower front portion, and having a lower shear jaw connected rigidly there-

with, said housing overlying the lower jaw and inclosing the upper jaw and a link pivotally connected with the jaws and with the handle first mentioned, substantially as described.

70 10. In combination in a machine of the class described, a pair of jaws, a needle with tongue cutting and folding means mounted on one jaw, a shear plate on the other jaw, handles for moving the jaws toward and from each other while maintaining their parallelism, the said other jaw with its shear plate being rigidly connected with one of the handles and being adjustable in relation thereto in a direction at right angles to the direction of closing movement of the jaws, substantially as described.

75 11. In combination in a machine of the class described, a pair of jaws, a needle with tongue cutting and folding means mounted on the upper jaw, a shear edge on the lower jaw, an upper handle, a lower handle and a housing carried thereby, said housing inclosing the upper jaw together with the parts carried thereby, said housing having forwardly extending ears and means for adjustably connecting the lower jaw with the said ears, substantially as described.

80 12. In combination, the upper and lower jaws, a needle with tongue cutting and folding means carried by one jaw, a shear edge carried by the other jaw, a handle having sides embracing the jaws, slidably connected with the carrying jaw of the tongue cutting means and pivotally connected with the means and pivotally connected with the shear jaw, links pivotally mounted on the inner faces of the sides of said handle, and pivotally connected to the outer sides of the jaws, and a handle rigidly connected with the shear plate carrying jaw, substantially as described.

85 13. In combination the upper and lower jaws, a needle with tongue cutting and folding means carried by one jaw, a shear edge carried by the other jaw, a handle having sides embracing the jaws, slidably connected with the carrying jaw of the tongue cutting means and pivotally connected with the shear jaw, links pivotally mounted on the inner faces of the sides of said handle, and pivotally connected to the outer sides of the jaws, a handle rigidly connected with the shear jaw, and a housing rigidly connected with the last mentioned handle partly inclosing and partly overhanging the lower jaw and inclosing the upper jaw with its attached parts, substantially as described.

90 14. In combination in a machine of the class described, upper and lower jaws, handles for operating the jaws, tie forming elements carried by the jaws, a spring stripper plate carried by the lower jaw and an arm connected with the stripper plate at a point intermediate of the length of said plate and

in rear of the tie forming elements for lifting the stripper plate, said arm extending up across the space between the jaws and being operated from the movement of the upper jaw, substantially as described.

12. In combination in a machine of the class described, two jaws, tie forming elements carried thereby, a spring stripper plate mounted on one jaw, means for moving the jaws toward and from each other, said stripper plate having an integral arm extending up from a point intermediate of its length, and means engaging the upper end of said arm and having the same rate of movement as the jaws for raising it as the upper jaw is lifted.

13. In combination in a machine of the class described, two jaws, tie forming elements carried thereby, means for operating the jaws, a stripper plate between the jaws having a pair of arms struck up therefrom at a point intermediate of its length and in rear of the tie forming elements, said arms embracing the upper jaw, and means connected with the upper jaw for operating said arms, substantially as described.

14. In combination the two jaws, tie forming elements carried thereby, a pair of links embracing the jaws and pivotally connected thereto, means for operating the jaws, and a stripper plate having a pair of arms, one at each edge extending to the upper jaw and engaging the upper edges of the links to be operated thereby, substantially as described.

15. In combination, the two jaws, tie forming elements carried thereby, means for operating the jaws, a stripper plate between the jaws having an integral reduced tail portion, secured to one jaw, and integral arms, one at each edge extending up from a point intermediate the length of the plate and means engaging the upper ends of the arms and having the same rate of movement as the jaws for lifting the stripper plate, substantially as described.

16. In combination the two jaws, tie forming elements carried thereby, a handle rigidly connected with one jaw, a handle pivotally connected with said jaw and having operating connection with the other jaw, a pair of links embracing the jaws and arranged upon the inner faces of the sides of the pivoted handle, said links having hollow journals struck out therefrom and fitting openings in the sides of the pivoted handle, substantially as described.

17. In combination a pair of jaws, tie forming elements carried thereby, one of said jaws having a shearing edge, handles for moving the jaws toward and from each other, a housing rigidly connected with the shear carrying jaw and having edges overhanging said jaw, a spring stripper plate and means for lifting the same, said overhanging edges serving to arrest the lifting

movement of the stripper plate, substantially as described.

18. In combination a pair of jaws, tie forming elements carried thereby, one of said jaws having a shearing edge, handles for moving the jaws toward and from each other, a housing rigidly connected with the shear carrying jaw and having edges overhanging said jaw, a spring stripper plate and means for lifting the same, said overhanging edges, serving to arrest the lifting movement of the stripper plate, said lifting means exerting its force at a point intermediate the length of the stripper plate and in rear of the tie forming elements, and said overhanging edges being substantially parallel with the shear member, substantially as described.

19. In apparatus of the class described, a punch having side walls, a folder within the punch consisting of a spring metal strip having a work end, said strip being curved over at its upper end, extending thence downwardly, thence curved forwardly toward the working portion, and thence upwardly, with means for holding said upwardly extending portion, substantially as described.

20. In apparatus of the class described, a punch having side walls, a folder within the punch consisting of a spring metal strip having a work end, said strip being curved over at its upper end, extending thence downwardly, thence curved forwardly toward the working portion, and thence upwardly, with means for holding said upwardly extending portion, the latter at its upper end being notched to receive the upper curved portion, substantially as described.

21. In combination in a machine of the class described, two jaws, a punch having side walls fitting within one jaw, a needle having side flanges and also fitting within said jaw, the edges of which flanges abut against the edges of the side walls of the punch, and means bearing on the punch and needle respectively for holding them together and to their carrying jaw.

22. In combination in a machine of the class described, a pair of jaws with means for operating them, a punch, folder and needle carried between the walls of one jaw, said punch having side walls, and the folder having a base portion to fit against the edges of the sides of the punch, and a needle clamping the base portion of the folder between itself and the punch, with means for holding said punch and needle together, substantially as described.

23. In combination in a machine of the class described, a pair of jaws with means for operating them, a punch, folder and needle carried between the walls of one jaw, said punch having side walls, and the folder

having a base portion to fit against the edges of the sides of the punch, and a needle clamping the base portion of the folder between itself and the punch, with means for holding said punch and needle together, the said folder having its base portion lying between its main working portion and a turned down connecting portion, and the needle having side flanges forming the bearings to engage the punch and receive the attaching portion of the folder between them and the punch, and means for holding the punch and needle in place, substantially as described.

24. In combination the two jaws with

operating means, a punch having side walls, a folder within the punch having side lugs fitting against the edges of the side walls, a needle having flanges fitting against the edges of the side walls of the punch, and 20 lugs on the flanges of the needle and side walls of the punch fitting respectively above and below the lugs on the base of the folder, substantially as described.

In testimony whereof, I affix my signature in presence of two witnesses.

GEORGE P. BUMP.
